ART OF MANUFACTURING FOLDED PAPER
ARTICLES

Samuel J. Campbell, Green Bay, Wis.

Application July 31, 1933, Serial No. 682,930

9 Claims. (Cl. 270—21)

This invention relates to improvements in the art of manufacturing folded paper articles.

One of the primary objects of the invention is to provide a novel and very compactly organized apparatus for the folding and severing of a paper web in the manufacture of folded paper articles. It is also a purpose to provide a machine capable of producing a large number of different types of folded paper articles with comparatively minor adjustments or substitution of parts.

More specifically stated, the objects of the invention are: the provision of a direct feeding machine for folding, packing, and subsequently cutting a web to produce folded paper articles, the various portions of the apparatus acting on the web being substantially aligned; the provision in a single unitary structure of means for embossing one or more webs, printing at least one of the webs, folding, packing, and subsequently cutting the webs to produce the completed articles, whereby the entire operation is conducted in synchronism on a single piece of apparatus; the provision of a novel organization of folding rolls and packing means, the folding rolls being vertical and having grooves in which the packing fingers act to perform the combined functions of strippers and packers to deliver the folded material directly from the rolls to the packing guides.

The provision of means for avoiding the streaking or the spoiling of the paper cut by a paper saw, whereby it is made practicable for the device to act in a continuous operation on a previously folded and packed web to sever folded paper articles therefrom comprises the subject matter of a companion application, Serial Number 74,042, filed April 13, 1936, entitled Art of manufacturing folded paper articles.

40 In the drawings:

Figure 1 is a side elevation of a folding, packing and cutting apparatus embodying the invention.

Figure 2 is a front elevation of the apparatus shown in Figure 1.

Figure 3 is a plan view of the apparatus shown on Figure 1.

Figure 4 is an enlarged detail view in horizontal section showing the cutting knife and the guard therefor.

Figure 5 is an enlarged detail view taken in section in the plane indicated at 5—5 in Figure 2.

Figure 6 is a front elevation of the parts shown in Figure 5 taken in the plane indicated at 6—6 in Figure 5.

Figure 7 is a plan view on a reduced scale showing diagrammatically an elaboration of the machine illustrated in Figures 1 to 6.

Figure 8 is a side elevation of the mechanism shown in Figure 7, such mechanism also being illustrated diagrammatically.

Like parts are identified by the same reference characters throughout the several views.

The folding, packing, and cutting apparatus shown in Figs. 1 to 3, comprises a portion of the apparatus shown in Figs. 7 and 8, but it is susceptible of independent use and hence will be described in considerable detail. The apparatus herein disclosed represents an improved means for the practice of the method disclosed in United States Letters Patent to Winter, No. 1,425,071, issued August 8, 1922.

The general operation of the machine with particular reference to Figs. 7 and 8

20 The webs 10 and 11 drawn from parent rolls 12 and 13 respectively, pass in superimposed relation between one or more sets of embossing rolls. The embossing rolls 14 and 15 may emboss the general design of a napkin upon the webs 10 and 11, while rolls 16 and 17 may print a suitable trade mark thereon. One or more of the webs leaving the embossing rolls may be printed in passing between platens 18 and press rolls 19 which are supplied with ink by the customary train as shown in Fig. 8.

25 The embossed and/or printed webs enter the folding, packing, and cutting apparatus across a suitable forming plate or plates 20, which fold the web longitudinally in a manner well known to the art. The folded web is squeezed between the rolls 21 and passes directly between the folding rolls 22 and 23. The squeeze rolls 21 and folding rolls 22 and 23 are rotatable on vertical axes and have sufficient length so that a plurality of webs may be acted upon simultaneously thereby.

30 The folding rolls 22 and 23 are equipped with any suitable paper engaging means, and are arranged to act alternately upon the paper so that the web is engaged first by one roll and then by the other, to be folded in zigzag convolutions. There are several web engaging means well known to the art. Fig. 3 illustrates broadly vise jaws and tucking blades for this purpose, but any other suitable means may be substituted for the purposes of the present application.

35 In the diagrammatic drawings of Figs. 7 and 8, the stripper and packer fingers are not disclosed. They will be described hereinafter in connection

50

55

with Figs. 1 to 3. It is sufficient for the purposes of this general description to note the fact that the folded and convoluted web is discharged directly from the folding rolls 22 and 23 on to the 5 packer guides 24 and 25 where it is acted upon by a cutting knife or saw 26 which may or may not have teeth, according to the particular requirements of the paper stock of which the web is composed.

10 Having described the general operation of the machine, I shall now refer in detail to the web folding, packing, and cutting mechanism shown in Figs. 1 to 6.

15 *The folding, packing, and cutting mechanism.*

The folding, packing, and cutting mechanism of the present invention may be used to produce a wide variety of napkin or other paper article folds, according to the type of former employed. In Figs. 7 and 8 I have shown the familiar "triangle plate" at 20, which folds the web just once in a longitudinal direction to produce the so-called "quarter" folded article. Interchangeable therewith in the preferred form 20 of the apparatus, are forming plates for producing any other desired type of fold. Figs. 1 and 3 show a forming plate 30 having a series of converging channels into which the fingers 31 force the web to produce a series of longitudinal folds. 25 The forming plates illustrated in Figs. 1 and 3 deliver between the squeeze rolls 21 a sufficiently folded web to produce a "sixteenth" fold napkin. The folded web stands on edge as shown at 100 in Fig. 1. From the squeeze rolls 21 it passes 30 directly between the folding rolls 22 and 23.

The folding rolls have peripheral grooves at 32 in which operate the packer and stripper fingers hereinafter to be described. As above noted, the folding rolls are so made as to engage the longitudinally folded web 100 alternately to draw it first in one direction and then the other, so as to produce a series of zigzag convolutions in a horizontal plane upon the packer guides 24 and 25. In accordance with one conventional type of 45 machine, I have illustrated tucker blades at 34 in each of the rolls 22 and 23 co-acting with vise jaws 35 in the other roll, to thrust the paper into the vise, first of one roll and then the other.

Laterally adjacent the folding rolls 22 and 50 23 are rock shafts 37 and 38. Each of these is provided with a set of stripping and packing fingers 39 which normally ride in the grooves 32 of the respective rolls, as shown in connection with roll 22 in Fig. 3, but are movable out of the 55 grooves as shown in connection with roll 23 in Fig. 3, to pack the previously completed transverse fold in the web. Each of the rolls carries a crank pin 40 which transmits motion through a connecting rod 40' to the rock shaft 37, 38 60 of the other roll.

The longitudinally and transversely folded and packed web is delivered on to the packing guides 24 and 25 between the adjustable side plates 41 and against the resistance of the weights 42 which 65 are movable longitudinally of the guides along the slots 43 therein. The folded, packed, and convoluted web is now sawed or cut by the knife 26 to produce two sets of folded and packed paper articles, such as napkins or the like.

70 The saw or knife preferably comprises a band knife operating over two pulleys 45 and 46, the upper pulley 45 being adjustable to maintain the knife under proper tension, and the lower pulley being driven by chain 47 from the drive 75 gearing which is concentrated in the bottom of

the machine as shown in Fig. 2. The small motors 48 are available to be operated when the knife 26 requires sharpening. The motors are adjustable and are provided with abrasive wheels 49, as best shown in Figs. 2 and 3. They may operate on the knife while the machine is in operation without soiling the paper, due to the feature now to be described.

A knife used without special protection will 10 discolor the severed sheets upon which it acts. This discoloration is produced even if the knife is not sharpened while in use. It results partly from small particles of metal and dirt carried by the knife partly from material worn from the knife while in use, and partly by the friction 15 upon and possible scorching of the web due to the rapidity of motion of the knife.

On the frame of the machine just beyond the abrasive wheels 49 in the direction of knife movement, is a cleaning device 50 shown in detail in 20 Figs. 5 and 6, which comprises a notched housing 51 packed with felt at 52 through which the knife blade 26 operates. This cleaning device removes foreign matter from the knife, particularly such as accumulates during the sharpening 25 operation. In addition, however, it is very important that the paper be protected from the frictional abrasion of all portions of the knife except the edge used in cutting through the convoluted web.

Fig. 4 shows in detail a guard 55 which is illustrated in Figs. 1 and 2. A pair of plates connected together about a spacer 56 converge at 57 on opposite faces of the annulus knife 26, immediately adjacent the cutting edge 58 thereof. As soon as the knife has severed the folded and convoluted web, the folded sections or articles are separated on the guides 24 and 25 by the converging marginal portions 57 of the guard plates, so that the area of the band knife required to give it suitable strength will not contact the margins of the severed articles. It has been found that the use of such a guard enables the satisfactory commercial production of clean edged articles, such as could not otherwise be 45 produced.

Operation

The operation of the apparatus will be briefly 50 reviewed.

The webs 10 and 11, delivered horizontally from parent rolls 12 and 13, may, if desired, be embossed and printed on their way to the folding, packing, and cutting apparatus. Where the cutting is deferred until after the embossed 55 and printed articles have been folded and packed in synchronism with the embossing and printing mechanism, the exact registration of the embossed and colored design with the ultimately folded and severed sheet is assured.

It will be understood that the driving connections of the embossing, printing and folding apparatus will be suitably synchronized, and that each convolution of the folded web will include two of the embossed or printed designs, the space 65 between such designs registering with the line upon which the convoluted web is severed by the knife 26.

The one or more webs enter the folding and cutting apparatus approximately horizontally 70 across forming plates which produce the required longitudinal folds. The longitudinally folded web is creased in the vertical plane in which it is delivered from the forming plates, and is passed between the folding rolls which 75

turn on vertical axes to produce the necessary transverse folds in regular convolutions prior to the cutting of the individual sheets from the web. The folded and convoluted web is preferably packed prior to cutting in order to facilitate the operation of the band knife which operates in a given position intermediate the path upon which the packed and convoluted portions of the web are forced. The movement of the convoluted portion of the web past the knife severs the web in between the transverse or convolution-folds and leaves the completed folded product in two rows on each side of the knife.

The present machine is a multiple machine handling a plurality of webs with a single set of creasing and folding rolls and a single knife. The rolls may be extended to produce a machine of any desired capacity.

The substantially horizontal movement of the web in passing through the machine is a feature making for great compactness, simplicity and economy of construction. As above noted, the driving gearing is all disposed at the bottom of the machine and is thereby enclosed to prevent possible injury to the operator. The vertical disposition of the folding and creasing rolls enables them to be driven directly from the mechanism at the bottom of the machine. The exact details of the driving connections are not disclosed because it will be obvious to anyone skilled in the art how driving connections may be organized to operate the various shafts disclosed.

I claim:

1. The combination with means for impressing designs successively upon a continuous web, of synchronously operable folding means arranged to act upon said web to provide longitudinal folding thereof, a second folding means operable

upon said web transversely thereof and arranged to register successive folds in opposite directions with central portions of the designs impressed upon said web, whereby to produce a series of convolutions each containing portions of successive designs, and means for severing the successive convolutions intermediate the design portions carried thereby, whereby to produce a plurality of rows of folded articles bearing designs in proper registry therewith.

2. Paper converting apparatus comprising the combination with forming means for the longitudinal folding of a web, of means for transversely folding said web in the course of its delivery, and means in the path of the transversely folded web for severing said web intermediate the transverse fold lines therein.

3. Web converting apparatus comprising the combination with folding rolls upon upright axes provided with folding means and alternately engageable with a web fed between said rolls, whereby to deliver such a web in convoluted folds, a guide in a position to receive the convoluted web, means resisting the advance of the convoluted web along said guide, means for packing the convoluted web against said resisting means and thereby feeding said convoluted web along said guide, and means in the path of said packed and convoluted web for cutting the successive convolutions thereof in the course of its advance.

4. Paper converting apparatus comprising the combination with folding rolls operable upon vertical axes and provided with peripheral grooves, of rock shafts disposed adjacent said

rolls, and projecting into the grooves of said rolls, and means for periodically oscillating the respective rock shafts in a direction to strip from the respective rolls a web previously engaged thereby.

5. Paper converting apparatus comprising the combination with a guide for a convoluted paper web, of a pair of folding rolls on vertical axes arranged to convolute a web and to discharge the web adjacent said guide, said rolls having peripheral grooves, rock shafts adjacent said rolls, stripping fingers receivable in the grooves of said rolls and carried by the respective rock shafts, web engaging means carried by the respective rolls and alternately operable upon said web for the convolution thereof, and means for oscillating said rock shafts alternately in a direction to withdraw their respective fingers from said grooves and to advance the convolutions of said web.

6. Paper converting apparatus comprising the combination with embossing means, means for feeding a plurality of webs in a superposed relation to be acted upon concurrently by said embossing means, means for printing one of the embossed webs in registry with the embossing thereon, means for longitudinally folding the webs, means for folding the webs transversely at points disposed centrally in their embossed areas, and means for severing the webs intermediate their respective embossed areas, whereby to provide prefolded embossed sheets.

7. Paper converting apparatus comprising the combination with embossing means, means for feeding a plurality of webs in a superposed relation to be acted upon concurrently by said embossing means, means for printing one of the embossed webs in registry with the embossing thereon, means for longitudinally folding the webs, means for folding the webs transversely at points disposed centrally in their embossed areas, and means for severing the webs intermediate their respective embossed areas, whereby to provide prefolded embossed sheets, the transverse folding means and the web severing means being common to the several webs.

8. The combination with a plurality of web feeding devices and means individual to said devices for longitudinally folding the web supplied thereby, of a single set of folding rolls common to the several devices and arranged to fold into transverse convolutions the longitudinally folded webs supplied by said devices, and a single cutting means acting upon the several webs intermediate the transverse fold lines thereof to sever the folded and convoluted webs, whereby to produce concurrently a plurality of stacks of quarter folded paper articles.

9. Paper converting apparatus comprising the combination with a plurality of parent roll supports, of a single embossing means for acting concurrently upon the webs drawn from said rolls, a separate printer for printing at least one of said webs, folders individual to the respective webs for producing longitudinal folds therein, and a transverse folding device common to the several webs for correspondingly convoluting the several webs simultaneously, together with cutting means disposed in the path of the convoluted webs for severing them intermediate the transverse convolution folds, whereby to divide each such web into a plurality of stacks of quarter folded paper articles.
